Inventor:

UNITED STATES PATENT OFFICE.

JACQUES ALBACHARY, OF DRESDEN, GERMANY.

DESIGN FOR A DRINKING-CUP.

SPECIFICATION forming part of Design No. 30,008, dated January 17, 1899.

Application filed July 8, 1898. Serial No. 685,443. Term of patent 7 years.

To all whom it may concern:

Be it known that I, JACQUES ALBACHARY, a citizen of the Kingdom of Saxony, and a resident of Dresden, in the Kingdom of Saxony and German Empire, have invented a certain new and original Design for Drinking Vessels, of which the following is a specification.

This invention relates to drinking cups or tumblers of cylindrical shape, as shown in the drawing, such as are used for the consumption of liquids of any kind.

The surface of the vessel is divided into parts by circular ribs or grooves *a*, intersected by vertical ones *b* in such a way as to form panels of different sizes, as shown in the fig-

ure. The ring of panels at the top is composed of narrower ones than the other ones. Within the panels thus obtained any suitable inscription or advertisement can be placed. 20

The vessel is provided with an ornamental projecting base part.

What I claim is—

The design for a drinking-cup as herein shown and described. 25

In testimony whereof I affix my signature in presence of two witnesses.

JACQUES ALBACHARY.
